UNITED STATES PATENT OFFICE.

RICHARD LEUMANN, OF CHAILLY-SUR-LAUSANNE, SWITZERLAND.

PROCESS OF WRAPPING AND MACHINE THEREFOR.

1,424,363.

Specification of Letters Patent. Patented Aug. 1, 1922.

Application filed March 31, 1921. Serial No. 457,484.

(GRANTED UNDER THE PROVISIONS OF THE ACT OF MARCH 3, 1921, 41 STAT. L., 1313.)

To all whom it may concern:

Be it known that I, RICHARD LEUMANN, a citizen of the Republic of Switzerland, residing at Chailly-sur-Lausanne, Switzerland, 5 have invented certain new and useful Improvements in Processes of Wrapping and Machines Therefor (for which applications for patents have been filed in Switzerland, November 19, 1914, Patent No. 70351; in Germany, November 27, 1914, Patent No. 293680, and in England, May 9, 1917, Patent No. 110882); and I do hereby declare the following to be a clear, full, and exact description of the invention, such as will enable 10 others skilled in the art to which it appertains to make and use the same, reference being had to the accompanying drawings and to letters or figures of reference marked thereon, which form a part of this specification.

It is already known to use a membrane when fixing capsules to the neck and to the head of bottles whereby the folding of the capsule is effected through the interposition 25 of the membrane by drawing the membrane over the bottle. In this case only part of an article is wrapped, which article is able to resist to a greater pressure. Further it is known to hold a cube to be wrapped simultaneously with the wrapper at two opposite 30 sides by means of one finger at each side and to fold the wrapper by drawing the cube past folding planes.

This invention has for its object to provide improvements to a method and a machine for completely wrapping single articles of any shape, such as chocolate bonbons and other single sweets in a wrapper of the type wherein the wrapper that has been brought 35 previously over the article is first folded hood-fashion around the article, and then closed on the underside of the article by means of a membrane arranged on a frame, which membrane has been slipped over the 40 article by the upward movement of the article between two conveyor fingers that are arranged one above the other and grip the article, the wrapper and the membrane between them.

An essential feature of the process according to the present invention consists in the fact that the article after the membrane has been slipped over it, is so engaged at two points opposite to each other at the side that

is not yet wrapped that the article is firmly held and the wrapper together with the membrane is partially caused to lie against that side that is not wrapped, whereupon folding fingers crush together the portion of the wrapper projecting beyond that side of the article consecutively in two different directions; finally the wrapped article is released from said lateral grip.

The accompanying drawings illustrate a constructional example of a machine for carrying out the said process.

Fig. 1 is a side view of the machine and Fig. 2 is a plan view thereof,

Fig. 3 illustrates the essential part of the machine in a vertical longitudinal section.

Fig. 4 shows on a larger scale a detail of the hooked arms which support the article;

Figs. 5, 6 and 7 are vertical sections drawn to a larger scale of parts of the machine, for the purpose of illustrating successive different positions of working;

Figs. 8, 9 and 10 are plans showing further parts of the machine likewise in different successive working positions;

Figs. 11, 12 and 13 show the wrapper in position on the article in different stages of the wrapping, and

Fig. 14 illustrates a modification of a part of the machine.

As is shown in the example, the improved machine for completely wrapping a single article, comprises a turnably mounted table 1, by means of which the articles to be wrapped are conveyed to the place where the wrapping is carried out. The table 1 is provided with cup shaped recesses 3 for taking up the articles (such as bonbons). The recesses 3 have in their bases apertures 3^a, which are smaller than the bonbon, for the passage therethrough of a finger 5 which moves up and down in a fixed vertical guide 4, under the table. A second finger 6 arranged above the finger 5 and in alignment with the latter is adapted to cooperate with the finger 5; it moves up and down in a fixed vertical guide 7 situated above the table 1. A table 11 provided with an aperture for the passage therethrough of the bonbon 2 and provided with stops 10 at its front edge is arranged directly over the table 1. Sheets 12 consisting for instance of tin foil, paper, etc. intended to serve as the wrappers are brought upon this table in regular intervals

of time by means of two rollers 8 and 9 of a paper feed apparatus which will be described hereinafter.

Above the table 11 there is arranged a membrane 13 consisting of an elastic material for instance rubber, which is fixed on the horizontal frame 14. The membrane 13 can be caused to bulge downwardly as well as upwardly through an aperture 15 in the frame 14. On the frame 14 there are mounted two pairs of folding fingers 16 and 17 arranged crosswise one over the other, which can rock on fixed fulcrums and are provided with anti-friction rollers 18 that extend through curved slots 19 in a ring 20 (Fig. 8) which is mounted to oscillate on the frame 14. The ring 20 is adapted to receive from a lever mechanism 21 a to and fro movement such that the fingers 16 and 17 will be caused to open and close alternately in pairs.

On the guide 7 there are pivoted two hooked arms 22 which are held apart in the position shown in Fig. 3, by means of a tension spring 23 (Fig. 4). These arms project with bent noses 24, 25 into the path of a head 6' which is provided on the lower end of the finger 6, which head is fitted with soft material 6'', for instance rubber.

The machine is actuated from a driving pulley 26 (Fig. 2) by which rotation is imparted to a spur wheel 28 fixed to the main driving shaft 29 by the interposition of a pinion 27. On this driving shaft the discs 30, 31 and 32 and the driving part 33 of a Maltese gear 33, 34 are mounted.

The cam disc 30 is provided at both sides with cam-grooves, the cam-groove 35 (Fig. 3) serving to actuate a knife 36 for cutting the strip of paper 71. The paper is fed from a roll 38 carried on a forked standard and is passed over a guide roll 39 and a guiding table 40 to a pair of rollers 41, arranged immediately in front of the knife 36.

A roller 42 fitted to the end of lever 44 loosely mounted on an axle 43 and adapted to swing about the latter, is co-acting with the cam groove 35; the lever 44 is linked by means of a connecting rod 45 to a lever 46 turnably mounted on an axle 47, the knife 36 being fixed to the free end of the lever 46.

The second cam groove 48 of the disc 30 serves to actuate the upper finger 6. To this end a roller 49 co-operating with the cam groove 48 is provided at the end of a lever 50 adapted to turn about the axle 43; a connecting rod 51 linked to the lever 50 causes a turning motion of the axle 52 and actuates thereby a rod 53 to the end of which the finger 6 is linked.

A cam groove 54 is provided on the disc 31 for the purpose of actuating the lower finger 5. A roller 55 co-operating with the cam groove 54 is mounted at the end of a lever 56 loosely fitted to the axle 43 and

adapted to turn about the latter, the lever 56 being connected by the rod 57 to the lower end of the finger 5.

The cam disc 32 is provided with a cam groove 58 serving to actuate the pair of folding fingers 16 and 17 i. e. to cause the scissor like movement of these folding fingers. To this effect a roller 59 co-operating with the cam groove 58 is fitted to the end of a lever 60 loosely mounted on the axle 43 and adapted to turn about the latter, which lever 60 actuates the rod 21 operatively connected to the ring 20.

The driving part 33 of the Maltese drive 33, 34 carries the roller 62 which causes the movement of the Maltese cross 34 and it carries also the ratchet disc 63 for the latter. The Maltese cross 34 is secured to a shaft 64 on which a worm wheel 65 is fixed which drives the toothed wheel 66 at the one end of a shaft 67. At the other end of the shaft 67 a bevel wheel 68 is mounted which meshes with a bevel wheel 69. The latter is fitted to the lower end of an axle 70, at the upper end of which the turn table 1 is fixed.

The feed of the paper strip 71 is effected by the pair of rollers 41, 41 situated on one side of the knife 36 and the pair of rollers 8, 9 situated on the other side of the knife 36 which rollers are driven by the shaft 64. To this effect a chain wheel 72 is fixed to the shaft 64 and the chain 73 co-acting with the chain wheel 72 imparts rotation to an axle on which a pinion 74 is mounted, which by the interposition of further pinions 75 rotates the two pairs of rollers.

The operation of the machine hereinbefore described and as shown in the drawings is as follows:

The bonbons 2 to be wrapped are placed into the recesses 3 of the turn table 1 and are intermittently fed to the wrapping members between the two fingers 5, 6 under the centre of the membrane 13. At every one quarter of a revolution of the Maltese cross 34 the turn table 1 is moved by the length of the pitch of the recesses.

When the driving pulley 26 is actuated a sheet 12 is severed from the strip of paper 71, which has been pulled up to the stop 10, by the knife 36, the finger 5 moves up and passes through the aperture 3a in the cup 3 situated over the finger 5, and pushes out the bonbon contained in the said cup. At the same time the finger 6 moves down taking with it the membrane 13 as shown in Figs. 1 and 3. A wrapper 12 has been previously placed upon the table 11 before the downward movement of finger 6. Now when the two fingers 5 and 6 grip the bonbon 2 tongs-fashion, they grip the wrapper 12 as well.

Then the two fingers still holding the bonbon 2, the wrapper 12 and the membrane 13 between them, move up until the bonbon has

reached the position shown in Fig. 5. The bonbon 2 is now wrapped completely except on its underside, by the wrapper 12, and outside the latter by the membrane 13. The 5 finger 5 now comes to a standstill. The finger 6 however continues moving upwards for some distance until its head 6' strikes the bent noses 24, 25 of the hooked arms 22. The hooked arms 22 are thereby moved 10 towards each other and they grip at two oppositely situated points beneath the bonbon 2 on the side which is not yet wrapped, so that the bonbon is held; at the same time the wrapper is pressed by the membrane 13 partly against the side which is not yet 15 wrapped. The finger 5 can now move downward, that is to say, move away from the side which is not yet wrapped.

Fig. 11 illustrates the bonbon in this stage 20 of the wrapping operation, the membrane being assumed to be removed. During the movements described up to now the folding fingers 16 and 17 are in the positions shown in Fig. 8; they now come also into 25 operation by the action of the cam disc 32 in order to wrap the bonbon also on its underside by crushing together the wrapper. Namely, first for instance the folding fingers 16 are caused by the to and fro rotation of the ring 20 through the angular distance b (Fig. 8) to move towards each other almost until they touch, and then to move away from each other again. Then by rotating the ring 20 to and fro through 30 the angular distance b (Fig. 8), the same operation takes place with the two folding fingers 17, so that the wrapper is crushed together successively in two different directions, and is folded also on the underside 35 of the bonbon with the exception of a loose end in the middle. The wrapper has now assumed the form shown in Fig. 12.

The movement of the folding fingers is effected in such a manner that the first pair 40 of folding fingers has opened before the second pair of folding fingers begins to close. After the four folding fingers have acted in this manner upon the wrapper 12, the fingers 5 and 6 move again towards each 45 other and grip the bonbon afresh, whereby the finger 5 presses the loose end of the wrapper (Fig. 12) against the underside of the bonbon (Fig. 13). As soon as the bonbon is gripped by the fingers 5 and 6, the hooked arms 22 release the bonbon (Fig. 5). The fingers 5 and 6 move downwards 50 whereby the bonbon is caused to move away from the membrane, and the said fingers place it completely wrapped into the afore- 55 said recess of the turn table 1.

As soon as the completely wrapped bonbon 2 is placed in the recess 3, the Maltese cross 34 is performing one quarter of a revolution whereupon the shaft 64 turns likewise by one quarter of a revolution. There-

by the feed motion of the turn table 1 to the extent of the pitch of the recesses is effected. Furthermore the chain wheel is turned by one quarter of a revolution whereby the paper 71 is fed by the action of the 70 pair of rollers 41 in between the pair of rollers 8, 9 by which the paper 71 is gripped and held during the cutting action. At the same time a severed sheet 12 is fed by the rotation of the pair of rollers 8, 9 above the 75 aperture of the plate between the membrane 13 and the bonbon 12 until it rests against the stop 10 of the plate 11. After this operation the conveyor fingers 5 and 6 are again actuated whereupon the above described series of operations is repeated.

The finger 5 may be covered with rubber or other soft material as indicated in the drawings in the case of finger 6.

The membrane instead of being fixed at 85 its periphery to the frame 14, may be fixed by means of springs 37, for instance in the manner shown in Fig. 14, in which case it can then be made of a less elastic material.

I claim:

1. In a process for completely wrapping single articles, such as chocolate bonbons and other single sweets, comprising feeding a wrapper to one side of a membrane, feeding the article to be wrapped to that side 95 of the wrapper remote of the membrane, gripping the article together with the wrapper and the membrane in the center of the latter and at the opposite side of the article by means of two fingers, holding the membrane at its circumference, moving the article the wrapper and the membrane in a direction perpendicularly to the plane of the membrane the article being pressed into the bulging membrane, gripping the article 100 pressed into the membrane at two lateral points opposite to each other and outside of the membrane and causing thereby the wrapper to partly lie against that side of the article that has not yet been wrapped, 110 crushing together the wrapper at said side in two different directions, releasing the article of said lateral grip, and removing the wrapped article from the bulged out membrane.

90

115

2. In a process for completely wrapping single articles, such as chocolate bonbons and other single sweets, comprising feeding a wrapper to one side of a membrane, feeding the article to be wrapped to that 120 side of the wrapper remote of the membrane, gripping the article together with the wrapper and the membrane in the centre of the latter and at the opposite side of the article by means of two fingers, holding the membrane at its circumference, moving the article the wrapper and the membrane in a direction perpendicularly to the plane of the membrane, the article being pressed into the bulging membrane, gripping the article 125 130

4
pressed into the membrane at two lateral points opposite to each other and outside of the membrane and causing thereby the wrapper to partly lie against that side of the article that has not yet been wrapped, removing said fingers from the side of the article not yet wrapped, crushing together the wrapper at said side in two different directions, releasing the article of said lateral grip, and removing the wrapped article from the bulged out membrane.

3. In a process for completely wrapping single articles, such as chocolate bonbons and other single sweets, comprising feeding a wrapper to one side of a membrane, feeding the article to be wrapped to that side of the wrapper remote of the membrane, gripping the article together with the wrapper and the membrane in the center of the latter and at the opposite side of the article by means of two fingers, holding the membrane at its circumference, moving the article the wrapper and the membrane in a direction perpendicularly to the plane of the membrane, the article being pressed into the bulging membrane, gripping the article pressed into the membrane at two lateral points opposite to each other and outside of the membrane and causing thereby the wrapper to partly lie against that side of the article that has not yet been wrapped, removing said fingers from the side of the article not yet wrapped, crushing together the parts of the wrapper projecting from said side in one direction, crushing together the once crushed part of the wrapper in a direction perpendicular to the afore mentioned direction, supporting the wrapped article at the side that has been wrapped last and pressing thereby the wrapper to the article, releasing the article of said lateral grip, and removing the wrapped article from the bulged out membrane.

4. In a process for completely wrapping single articles, such as chocolate bonbons and other single sweets, comprising feeding a wrapper to one side of a membrane, feeding the article to be wrapped to that side of the wrapper remote of the membrane, gripping the article together with the wrapper and the membrane in the center of the latter and at the opposite side of the article by means of two fingers, holding the membrane at its circumference, moving the article the wrapper and the membrane in a direction perpendicular to the plane of the membrane the article being pressed into the bulging membrane, gripping the article pressed into the membrane at two lateral points opposite to each other and outside of the membrane and causing thereby the wrapper to partly lie against that side of the article that has not yet been wrapped, crushing together the parts of the wrapper projecting from said side in one direction, crushing together the once crushed part of the wrapper in a direction perpendicular to the afore mentioned direction, releasing

the article from said lateral grip and removing the wrapped article from the bulged out membrane.

5. In a process for completely wrapping single articles, such as chocolate bonbons and other single sweets, comprising feeding a wrapper to one side of a membrane, feeding the article to be wrapped to that side of the wrapper remote of the membrane, gripping the article together with the wrapper and the membrane in the center of the latter and at the opposite side of the article by means of two fingers, holding the membrane at its circumference, moving the article the wrapper and the membrane in a direction perpendicularly to the plane of the membrane the article being pressed into the bulged membrane, gripping the article pressed into the membrane at two lateral points opposite to each other and outside of the membrane and causing thereby the wrapper to partly lie against that side of the article that has not yet been wrapped, removing said fingers from the side of the article not yet wrapped, crushing together the parts of the wrapper projecting from said side in one direction, crushing together the once crushed part of the wrapper in a direction perpendicular to the afore mentioned direction, supporting the wrapped article at the side that has been wrapped last and pressing thereby the wrapper to the article, releasing the article from said lateral grip, and removing the wrapped article from the bulged out membrane.

6. In a process for completely wrapping single articles, such as chocolate bonbons and other single sweets, comprising feeding a wrapper in between the article to be wrapped and the membrane, causing the membrane to completely enclose the article to be wrapped outside the wrapper and removing the membrane from the completely wrapped article.

7. In a process for completely wrapping single articles, such as chocolate bonbons and other single sweets, comprising feeding a wrapper in between the article to be wrapped and a membrane, pressing the article to the membrane and causing a bulging of the latter, squeezing the membrane over that side of the article not yet wrapped and removing the completely wrapped article from the membrane.

8. In a machine for completely wrapping single articles, such as chocolate bonbons and other single sweets, in combination, a membrane, means adapted to hold a wrapper parallel to said membrane, means adapted to hold the article to be wrapped to that side of the wrapper remote of the membrane, means adapted to move the article to be wrapped together with the wrapper and said membrane perpendicularly to the plane of the membrane so that the latter and the

5 wrapper situated between the article and the membrane are folded over the article except on one side, means for crushing together the membrane over said side not yet wrapped, and means for effecting the removal of the completely wrapped article from the bulged out membrane.

9. In a machine for completely wrapping single articles, such as chocolate bonbons 10 and other single sweets, in combination, a membrane, means adapted to hold a wrapper parallel to said membrane, means adapted to hold the article to be wrapped to that side of the wrapper remote of the membrane, 15 fingers adapted to grip the articles with the wrapper and the membrane, means operatively connected to said fingers to press the article against the membrane and cause a bulging of the latter whereby the article is 20 wrapped at all sides except one, folding members for crushing together the wrapper over said side not yet wrapped, and means for effecting the removal of the completely wrapped article from the bulged out membrane.

25 10. In a machine for completely wrapping single articles, such as chocolate bonbons and other single sweets, in combination, a membrane, a supporting part for a wrapper 30 provided with an aperture in its centre and arranged under said membrane, a device adapted to feed the articles singly under said supporting part, a finger adapted to lift the article together with said wrapper to the 35 membrane and causing the latter to bulge whereby the article is wrapped except at one side, folding fingers adapted to crush together the part of the wrapper projecting beyond said side of the article in two different 40 directions, mechanism for actuating the feed device and the folding fingers and mechanism for actuating said first mentioned finger and returning it into its initial position and to release the completely 45 wrapped article.

50 11. In a machine for completely wrapping single articles, such as chocolate bonbons and other single sweets, in combination, a membrane, a supporting part for a wrapper provided with an aperture in its centre and arranged under said membrane, a device adapted to feed the articles singly under said supporting part, a finger adapted to lift the article together with said wrapper 55 to the membrane and causing the latter to bulge whereby the article is wrapped except at one side, two pairs of folding fingers adapted to crush together the part of the wrappers projecting beyond said side of the article in two different directions, mechanisms for actuating said first mentioned finger and returning it into its initial position to release the completely wrapped article, and mechanisms to actuate the feed device and the folding fingers.

12. In a machine for completely wrapping single articles, such as chocolate bonbons and other single sweets, in combination, a membrane, means adapted to hold a wrapper parallel to said membrane, means adapted to hold the article to be wrapped, to that side of the wrapper remote of the membrane, means adapted to move the article to be wrapped together with the wrapper and said membrane perpendicularly to the plane 75 of the membrane so that the latter and the wrapper situated between the article and the membrane are folded over the article except on one side, means for gripping the article in the bulged membrane 80 at two opposite points of the side not yet wrapped so that part of the wrapper is caused to lie against said side, means for removing the holding means from the article, means adapted to crush together the membrane at the side not yet wrapped, means causing to return said holding means into the initial position, means adapted to remove said gripping means from the article, and means to effect the removal of the article from the bulged membrane.

13. In a machine for completely wrapping single articles, such as chocolate bonbons and other single sweets, in combination, a membrane, a supporting part for a wrapper provided with an aperture in its centre and arranged under said membrane, a device adapted to feed the articles singly under said supporting part, a finger adapted to lift the article together with said wrapper to the membrane and causing the latter to bulge whereby the article is wrapped at one side, hooked arms adapted to grip the article in the bulged membrane at two opposite points of the side not yet wrapped so that part of the wrapper 100 is caused to lie against said side, means adapted to remove said lifting finger from the free side of the article, two pairs of folding fingers adapted to crush together the part of the wrapper projecting beyond said 105 side of the article in two different directions, means adapted to lift the finger to bear against the article, driving means for actuating the feed device, the hooked arms, and the two pairs of folding fingers, means for 110 removing the hooked arms from the lower side of the article, and means to effect the removal of the article from the membrane.

14. In a machine for completely wrapping single articles, such as chocolate bonbons and other single sweets, in combination, a membrane, means to feed a wrapper between said membrane and the article to be wrapped, means adapted to move the membrane so that it bears against one side of the wrapper, 120 means causing the article to bear against the other side of the wrapper, means adapted to move the article, the wrapper and the membrane together in a direction perpendicular to the plane of the membrane so that the 125 130

- membrane covers the article except at one side, means to crush together the membrane at said side of the article, and means to remove the article from the membrane.
15. In a machine for completely wrapping single articles, such as chocolate bonbons and other single sweets, in combination, a membrane, a supporting part for a wrapper provided with an aperture in its center and arranged under said membrane, a device adapted to feed the articles singly under said supporting part, a finger adapted to lift the article together with said wrapper to the membrane and causing the latter to bulge whereby the article is wrapped except at one side, a second finger adapted to cause the membrane to bear against the wrapper previous to the article being lifted, means adapted to move the article to be wrapped together with the wrapper and said membrane perpendicularly to the plane of the membrane so that the latter and the wrapper situated between the article and the membrane are folded over the article except on one side, means for crushing together the membrane over said side not yet wrapped, and means for effecting the removal of the completely wrapped article from the bulged out membrane.
20. In a machine for completely wrapping single articles, such as chocolate bonbons and other single sweets, in combination, a membrane, a supporting part for a wrapper provided with an aperture in its center and arranged under said membrane, a feed device adapted to feed the articles singly under said supporting part, a finger adapted to lift the article together with said wrapper to the membrane and causing the latter to bulge whereby the article is wrapped except at one side, a finger adapted to cause the membrane to bear against the wrapper previous to the article being lifted, means adapted to return the second mentioned finger into its initial position simultaneously as the article is lifted, hooked arms adapted to grip the article in the bulged membrane at two opposite points of the side not yet wrapped so that part of the wrapper is caused to lie against said side, means adapted to remove said lifting finger from the free side of the article, two pairs of folding fingers adapted to crush together the part of the wrapper projecting beyond said side of the article in two different directions, means adapted to lift the finger to bear against the article, driving means for actuating the feed device, the hooked arms, and the two pairs of folding fingers, means for removing the hooked arms from the lower side of the article, and means to effect the removal of the article from the membrane.
25. In a process for wrapping, feeding a wrapper between an article to be wrapped and a yielding membrane, causing the membrane to press the wrapper snugly around the top and sides of the article to be wrapped, crimping the wrapper partially beneath the article, crushing the wrapper depending below the article in two directions, and then crushing the wrapper against the bottom of the article.
30. In a process for wrapping sweetmeats and the like, feeding a wrapper between the article to be wrapped and a membrane, causing the membrane to press the wrapper snugly into the article except on one side, and thereafter causing the wrapper to lie snugly against the side not yet wrapped.
35. In testimony that I claim the foregoing as my invention, I have signed my name.
